UNITED STATES PATENT OFFICE.

FRIEDERICH W. POLLE, OF GREENVILLE, MISSISSIPPI.

TURNING PLUG.

SPECIFICATION forming part of Letters Patent No. 334,722, dated January 19, 1886.

Application filed June 27, 1885. Serial No. 169,972. (No model.)

To all whom it may concern:

Be it known that I, FRIEDERICH W. POLLE, a citizen of the United States, residing at Greenville, in the county of Washington and 5 State of Mississippi, have invented certain new and useful Improvements in Faucets, of which the following is a specification, reference being had to the accompanying drawings.

My invention relates to spigots or faucets 10 intended especially for use in beer or other barrels, wherein it is desirable to frequently change the spigot from one barrel or keg to another.

It has for its main object to provide a wooden 15 spigot which will serve its purpose efficiently and will be durable.

It has for further objects to provide simple, 20 convenient, and efficient means whereby to prevent the cock from leaking.

25 It has for further objects other improvements, which will be hereinafter more fully described and claimed.

To these ends my invention consists in certain novel constructions, combinations, and 30 arrangements of the several parts, as will be set forth.

Referring to the drawings, Figure 1 is a side elevation, and Fig. 2 is a horizontal section, of my spigot. Fig. 3 is a detail view of my wear- 35 plate.

A denotes the body of any ordinary wooden spigot, which, as usual, is provided with the opening A', extended longitudinally from its inner end and terminating in the transverse 40 opening A², formed through the body A near its outer end. The opening A² is preferably tapered toward one end to receive the cock, presently described, and enables the same to be properly tightened as the parts are worn.

45 In this opening A², I fit packing B, of leather or other suitable material, to enable the proper fitting of the parts. The body A is re-enforced and strengthened by metallic bands C, encircling and secured to it. On the end I fit a metallic cap, C', which is adapted to receive the force in placing the faucet in the barrel. This cap and the bands prevent all splitting or fracture of the spigot and render the same much more durable.

50 In the use of wooden spigots experience has demonstrated that the inner end of same, which is inserted into the barrel, becomes soon

worn without and within the opening A' from the combined influence of the beer or other liquid and the hasty and careless manner in which they are removed from one barrel and inserted in another. To overcome this objection, and prevent this wear and damage, I provide the cap D, which fits on the inner end of the body A, and is provided with an 55 inwardly-turned tube, D', which fits in and closely to the sides of the outer end of body A'. By this cap I efficiently protect the outer end of the body A, both on the outside of same and within its bore A'. The cock E is 60 provided with a suitable handle, E', and is fitted to and turns within the opening A². I by preference form it of block-tin, so as to prevent corrosion and other damage from the fluid. This cock is provided with an opening, 65 E², which may be turned to register with opening A', and a third or discharge opening, fitted with tube F, is formed transversely through the body A² at about right angles to opening A². This last opening intersects the opening 70 A² at such a point that it will register with opening E² at the same time the said opening is registered with bore A'. By such arrangement the cock may be conveniently turned so as to enable the passage of liquid through 75 80 openings A' A² and out of spout or tube F.

On the side of the body A, I secure the wear and strengthening plate G, provided with an opening which registers with opening A² and fits closely on the cock E. In the outer end 85 of this plate G, I form slots G', in which rest the studs of the spring hereinafter described. The end of the cock E projects beyond the wear-plate G, and is threaded to receive the nut H. A spring, I, of flat metal, is placed on 90 the cock E, and bears between nut H and the wear-plate G, having its ends properly bent to bear against the said wear-plate and give the desired tension against the inner side of the nut H necessary to hold the cock securely 95 in its bearings in the body. By turning the nut H on the cock the tension of the spring may be varied, and the nut may be held at any point of adjustment by a screw turned through it and impinging on the thread of the 100 cock. The outer ends of the spring I are provided with studs I' I', which project one in each of the slots G'. These studs, it will be seen, are free to move longitudinally in the

said slots as the spring is expanded; but they serve efficiently to prevent the rotation and displacement of the spring with the movement of the cock. The wear-plate G thus serves to 5 prevent damage to the body A, and also as a means for retaining the spring in proper operating position. It will be understood that instead of discharging through spout F the said spout might be dispensed with and the 10 cock made hollow toward and out of its threaded end, so the liquid might be discharged directly through and out of the cock.

By the described devices it will be seen the 15 wood of the faucet is protected and preserved intact. The nut F may be turned upon the cock against the spring; the effect being to draw the cock tight in its opening and retain it firmly in such position, and the set-nut is held from being turned by the frequent turning 20 of the cock by the nut set against the thread of the cock, as before described. The packing B, fitted in the hole A², renders the joint of the cock and body air-tight.

Having thus described my invention, what 25 I claim is—

1. In a faucet, the combination of the body,

the cock, the wear-plate G, provided with slots G', the spring I, placed on the cock and provided with studs I', fitted and movable in slots G', and the nut turned on the cock and 30 adjustable against the spring I, substantially as set forth.

2. The faucet, substantially as herein described and shown, consisting of the body A, provided with openings A' A², the cap D, embracing the inner end of the faucet and provided with tube D', projected into the inner end of opening A', the cock E, having its end extended beyond the body and threaded, the wear-plate G, having the slots G', the spring 35 I, having studs I', fitted in slots G', and the nut H, turned on the cock and against spring I, and provided with a set-screw, H', whereby it may be fixed at any desired point, substantially as set forth.

In testimony whereof I affix my signature in presence of two witnesses.

FRID. W. POLLE.
